(57) **CLAIM**

The ornamental design for a top assembly with cap for baby bottle, as shown and described.

DESCRIPTION

FIG. 1 is a perspective view of a top assembly with cap for baby bottle showing my design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The broken lines in FIG. 7 illustrate portions of the top assembly with cap for baby bottle which forms no part of the claimed design.
